UNITED STATES PATENT OFFICE

128,370

DESIGN FOR A BURIAL VAULT IDENTIFICATION PLAQUE

Wilbert W. Haase, Forest Park, Ill., assignor to
Wilbert W. Haase Co., Forest Park, Ill., a cor-
poration of Illinois

Application February 3, 1941, Serial No. 98,673

Term of patent 14 years

To all whom it may concern:

Be it known that I, Wilbert W. Haase, a citizen of the United States of America, residing at Forest Park, in the county of Cook and State of Illinois, have invented a new, original, and ornamental Design for a Burial Vault Identification Plaque, of which the following is a specification, reference being had to the accompanying drawing, forming a part thereof.

Referring to the drawing:

Figure 1 is a plan view of a burial vault identification plaque, showing my new design; and Fig. 2 is a side elevational view.

The design is characterized by a centrally disposed smooth panel for identification matter, said panel being arranged in a surrounding field having a relatively rough surface, together with a picturesque panel element located adjacent an end of the centrally disposed panel, as shown in the drawing.

The identification matter appearing on the design is merely illustrative.

I claim:

The ornamental design for a burial vault identification plaque, as shown and described.

WILBERT W. HAASE.
